(57) **CLAIM**

We claim the ornamental design for a pump component, as shown and described.

DESCRIPTION

FIG. 1 is a top perspective view of a pump component in accordance with an embodiment of our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.

Any portions of the pump component shown in broken lines in the figures depict unclaimed environmental subject matter, are for illustrative purposes only, and form no part of the claimed design. Similarly, unshaded portions that appear between broken lines or beyond boundary or break lines in the figures form no part of the claimed design and indicate that a specific width, height and/or length forms no part of the claimed design.

It will be understood that all lines in the drawings, including broken and solid lines, are intended to convey the full disclosure and variations of the designs and such variations shall be understood to be fully described herein.
